REISSUED

UNITED STATES PATENT OFFICE

FREDERICK F. PAZZANO, OF WALTHAM, MASSACHUSETTS

TOOL

Application filed December 29, 1930. Serial No. 505,436.

This invention relates to certain new and useful improvements in tools, and the primary object of the present invention is to provide a tool especially adapted for the removal of automobile storage battery terminal clips, the object of the invention being to provide a tool equipped with a pair of jaws for loosening and tightening the clip nut, together with additional means adapted to be inserted in the confine of the clip for spreading the same to facilitate removal of the clip from the storage battery terminal.

A further object of the invention is to provide a tool of this character, which is comparatively simple in construction, consists of relatively few parts, and which will be found thoroughly efficient for the purpose designed.

Other objects and advantages of the invention will become apparent during a study of the following description, taken in connection with the accompanying drawing wherein:

Figure 1 is a side elevational view of the tool.

Figure 2 is a bottom plan view thereof.

Figure 3 is an edge elevational view of one of the jaws.

Figure 4 is an elevational view of the other of the jaws.

With reference more in detail to the drawing, it will be seen that the tool comprises a pair of levers 1 and 2 respectively, lever 1 adjacent one end thereof being provided with a lateral notch 3, and at the forward end of the notch having projecting laterally therefrom an arcuate jaw that on its concaved face is provided with teeth 5. Extending laterally from the lever 1 in a direction opposite to jaw 4 is an integral lug 6. Lug 6 is preferably disposed obliquely with respect to the longitudinal axes of the lever 1.

Lever 2 at one end thereof is provided with a lateral projection 7 provided on one side thereof with a notch 8 providing upper and lower stop shoulders 9 and 10 for engagement with corresponding edges of the lever 1 at the notch 3. The projection 7 is

pivoted within the notch 3 through the medium of a suitable pivot pin 11.

Projection 7 at its free end terminates in a jaw 12, which jaw 12 is in substantially the same plane as the jaw 4. Jaw 12 at its free end is provided with an arcuate series of teeth 13 for cooperation with the teeth 5.

Projecting laterally from the lever 2 oppositely with respect to the projection 7 is a lug 14 cooperable with the lug 6 as and for a purpose to be hereinafter made manifest.

In actual practice and when using the tool for loosening or tightening the nut of a storage battery terminal, the jaws 4 and 12 are moved into engagement with the nut by moving the levers 1 and 2 toward one another and then by suitably manipulating the tool, the nut may be threaded relative to its bolt for loosening or tightening the nut as desired.

To use the tool for spreading the clip of the battery terminal, levers 1 and 2 are moved away from one another for positioning the lugs 6 and 14 adjacent one another, and the lugs may be then inserted within the confines of the clip, one face of each lug 6 and 14 being suitably rounded to conformably engage a portion of the clip. While moving the levers 1 and 2 toward one another for spreading the lugs 6 and 14 apart the terminal clip will be "spread" or "expanded" thus facilitating removal of the clip from about the battery terminal.

It is thought that from the foregoing description taken in connection with the drawing a clear understanding of the operation, construction utility and advantages of a tool of this character will be had by those skilled in the art without a more detailed description.

It is to be understood while I have herein shown and described a preferred embodiment of the invention, that the same is susceptible of modifications, improvements and variations coming within the scope of the appended claim:

Having thus described my invention what I claim as new is:

A combination tool comprising in combination a pair of pivotally mounted levers, provided at their corresponding ends with cooperating work spreading fingers, one of 5 said handle members having a transverse slot and the other of said handle members having a lateral projection operable within the slot, and terminating at its free end in a portion inclined to the axes of the handle 10 members and provided with a convex toothed work engaging face, and said first-mentioned handle member adjacent the slot provided with a lateral projection having a concave toothed work engaging face con- 15 fronting the work engaging face of said inclined portion, and said work spreading fingers confronting one another and adapted to engage one with the other when the handle members are spread apart to thereby 20 limit relative swinging movement of the handle members.

In testimony whereof I affix my signature.
FREDERICK F. PAZZANO.
